KNITTED FABRIC

Robert H. Lawson, Pawtucket, R. I., assignor to
Hemphill Company, Central Falls, R. I., a
corporation of Massachusetts

Application April 24, 1935, Serial No. 18,023

6 Claims. (Cl. 66—179)

This invention relates to knitted fabrics and methods of knitting and more particularly to the knitting of so-called split-work fabric.

In the drawings:

- 5 Fig. 1 is a view of a stocking or half hose more or less diagrammatically illustrating split-work; Fig. 2 is a view showing the outer face of a fabric and a few wales and courses thereof knitted with two yarns, each yarn being knitted into 10 a portion of the fabric and the two portions of the fabric being connected by two so-called suture wales; and
- Figs. 3-8 are views similar to Fig. 2, but showing 15 different forms of sutures.
- 15 The stocking or half hose shown in Fig. 1 is designated by the numeral 1, the top rib and/or welt portion of the stocking being shown at 2. The leg of the stocking is shown at 3 while 4 indicates diagrammatically the suture line connecting the instep 5 to the high splice 6 and to the sole 7. The heel is indicated at 8, the point of the heel suture at 8' being shown as spaced from the suture 4. The toe of the stocking is indicated at 9.
- 20 Referring to Fig. 2, successive courses constituting the instep portion 5 of the stocking are designated by the numerals 10, 11, 12 and 13 whereas the courses companion thereto are indicated at 10', 11', 12' and 13'. The directions 25 of knitting of the courses 10 and 11 constituting the instep portion 5 of the stocking are indicated by the numerals 14 and 15 respectively, whereas the numerals 16 and 17 respectively, indicate the directions of knitting of the courses 10', 11'. The 30 courses 12 and 13 are duplicates of the courses 10 and 11 respectively and likewise the courses 12' and 13' are duplicates of the courses 10' and 11'. For convenience of description a few needles are indicated at 18, 19, 20 and 21, the needle 18 35 knitting the instep yarn 22 only and the needle 21 knitting the yarn 23 only, whereas the needles 19 and 20 are specially operated to knit both yarns.

In describing a complete cycle of operations 40 the knitting of the courses 10, 11, 10' and 11' will be described in that order.

45 Although the fabric shown in Fig. 2 as well as the other fabrics shown in Figs. 3-8, can be knitted on various types of knitting machines, the 50 knitting is preferably effected on machines known as and similar to Banner knitting machines, said machines all having independent needles.

Assuming the needles 18, 19, 20 and 21 to be 55 mounted in a rotary needle cylinder, although this is not essential, and the knitting to be pro-

ceeding in the direction of the arrow 14, the needle 18 and preceding needles knit the yarn 22 and the following, suture needle 19 likewise knits the yarn 22, the said needles 18 and 19 drawing loops of yarn through previous course loops. On 5 that stroke of the needle cylinder, the needle 20 does not engage the yarn 22 but upon the needle cylinder reversing its direction of movement to knit course 11, the yarn 22 is wrapped around the shank of the needle 20 below its latch. The 10 needle 19, however, during the knitting of this course 11, is in a low position and does not engage the yarn 22 although the needle 18 and the following needles all knit the yarn 22 in the usual manner. Now as the needle cylinder continues 15 its movement as in a clockwise direction, the course 10' is knitted at the other and commonly called main side of the machine whereat the yarn 23 is fed to the needles. As the movement of the needle cylinder continues as aforesaid, 20 the needle 21 and preceding needles knit the yarn 23. The needle 20 engages the yarn 23 in its hook and draws a bight thereof through the previous course loop. On this stroke of the needle cylinder the needle 19 also knits the yarn 23. As 25 the direction of movement of the needle cylinder reverses, i. e., in an anti-clockwise direction, the course 11' is knitted in the direction of the arrow 17. In the knitting of this course the leading needle 19 is in an elevated position to permit the 30 yarn 23 to be wrapped around the shank and below the needle latch. Continued rotation of the needle cylinder causes the needles 20, 21 and following needles to knit the yarn 23 in the usual manner, thus completing a cycle. The 35 knitting of the course 12 and following courses is accomplished in the manner just described in connection with the knitting of courses 10, 11, 10', 11'.

In the fabric shown in Fig. 3, the same yarns 22 and 23 are shown, the courses knitted with the yarn 22 being designated by the numerals 25, 26, 27 and 28, whereas the courses knitted by the yarn 23 are designated by the numerals 25', 26', 27' and 28'. The directions of knitting of the 45 courses 25, 26, 25', 26', are indicated respectively by the arrows 29, 30, 31 and 32. Needles are shown at 33, 34, 35, 35'. The method of knitting the fabric shown in Fig. 3 is substantially the same as that described with respect to the fabric 50 shown in Fig. 2 except that the needle 34 which corresponds to the needle 19, Fig. 2, is held in an elevated position during the knitting of the course 26 which corresponds to the course 11, Fig. 2, so that the yarn 22 shall be wrapped around the 55

needle shank (but not knitted) and subsequently held between two bights of the yarn 23 as shown in Fig. 3.

In Fig. 4 courses 36, 37, 38, 39 correspond respectively to courses 10, 11, 12, 13 and likewise courses 36', 37', 38', 39' correspond to courses 10', 11', 12', 13', the arrows 40, 41, 42, 43 indicating the directions of knitting of the respective courses 36, 37, 36', 37', etc. The needles 44, 45, 46, 47 correspond to the needles 18, 19, 20, 21, Fig. 2. In knitting the course 36 the needle 44 knits the yarn 22 in the usual manner and suture needle 45 likewise knits yarn 22 drawing a bight thereof through loops of the yarn 23 previously formed. The needle 46 does not knit the yarn 22 during the knitting of the course 36 but upon the needles reversing their direction of movement the needle 46 knits the yarn 22 drawing a bight thereof through a loop of the yarn 23. The needle 45, however, does not knit the yarn 22 during the knitting of course 37 but the needle 44 and following needles knit the yarn as usual. As the needles continue knitting and approach the yarn 23 in the knitting of the course 36', the needle 47 knits the yarn 23 and likewise the needles 46 and 45 draw bights of yarn through loops drawn during the knitting of the course 37. Upon the needles again reversing their direction and moving in an anti-clockwise direction, the leading needle 45 is held in an elevated position to permit the yarn 23 to be wrapped around the needle shank and below the latch, the needles 46, 47, etc., knitting the yarn 23. The courses 38, 39, 38', 39' are knitted in the same manner as courses 36, 37, 36', 37'.

In the form of the fabric illustrated in Fig. 5, the yarn 22 is shown as being knitted into courses 48, 49, 50, 51, etc., while the yarn 23 is shown as being knitted into corresponding courses 48', 49', 50', 51', etc., the arrows 52, 53, 54, 55, indicating the direction of knitting of the courses 48, 49, 48', 49', etc. The needles 56, 57, 58, 59 knit in the following manner starting with the course 48 and assuming the needles to move with respect to the yarns 22, 23. The needle 56 and preceding needles knit the yarn 22 and the suture needles 57, 58 likewise knit the yarn 22 and draw bights thereof through the loops of the previous course. Upon the needles reversing their direction of movement, as to move in a clockwise direction, the leading needle 58 is maintained in an elevated position to permit the yarn 22 to be wrapped around the shank thereof and below the latch if latch needles be used. The needle 57, however, does not engage the yarn 22 during this movement or stroke of the needles but the needle 56 and following needles knit the yarn 22 in the usual manner. Continued movement of the needles in the clockwise direction causes the needles 56, 57, 58, 59 to approach the yarn 23 to knit the course 48' during the knitting of which the needle 59 and preceding needles knit the yarn 23 in the usual manner and the suture needles 58, 57 also draw loops or bights of yarn 23 through the loops of the yarn 22. The needles then reverse their movement and move in a counter-clockwise direction and during this stroke or movement of the needles the course 49' is knitted, the leading needle 57 being maintained in an elevated position to permit the yarn 23 to be wrapped around the shank and below the needle latch. The following needle 58 does not knit the yarn 23, but the needle 59 as well as the following needles knit the yarn 23 in the usual manner. The courses 50, 51, etc., and the courses

50', 51' are knitted in the same manner as courses 48, 49, 48', 49'.

In the form of the fabric shown in Fig. 6, the yarns 22 and 23 are knitted into courses 60, 61, 62, 63, etc. and 60', 61', 62', 63', etc., the arrows 64, 65, 66, 67 indicating the direction of knitting of the respective courses 60, 61, 60', 61'. This form of suture shown in Fig. 6 being a single needle suture, three needles 68, 69, 70 only are designated. Assuming the cycle of operations to begin with the knitting of the course 60 and with the needles moving in an anti-clockwise direction, the needle 68 knits the yarn 22 in the usual manner and the needle 69 also draws a bight or loop of the yarn 22 through a previous course loop formed of the yarn 23. The needle 70 and the following needles do not knit the yarn 22. When the needles reverse their direction of movement and move in a clockwise direction (course 61), the needle 69 knits the yarn 22 and draws a bight thereof through the loop drawn by the said needle during the knitting of the course 60. The needles 68 and following needles knit the yarn 22 in the usual manner. Continued movement of the needles causes the needles 70, 69, 68 to approach the yarn 23, the needles 70 and 69 knitting (course 60') the said yarn 23 in that order, the needle 68 and following needles not knitting the yarn 23. Upon the needles reversing their direction of movement and moving in an anti-clockwise direction (course 61'), the needle 69 which is the leading needle, is maintained in an elevated position to permit the yarn 23 to be wrapped around the shank of the needle and below the latch thereof, the needle 70 and following needles knitting the yarn 23 in the usual manner. The courses 62, 63, 62', 63' are knitted in the same manner as described with respect to the courses 60, 61, 60', 61'.

The fabric shown in Fig. 7 comprises courses 71, 72, 73, 74 and courses 71', 72', 73', 74'. The arrows 75, 76, 77, 78 indicate the directions of knitting of the courses 71, 72 and 71', 72', etc. In this form of the fabric two suture needles are employed and consequently needles 79, 80, 81, 82 are indicated. Beginning with the knitting of the course 71 and with the needles moving in a counter-clockwise direction, the needle 79 and preceding needles knit the yarn 72 as do the suture needles 80 and 81. The needle 82 and following needles do not knit the yarn 22. Upon the needles reversing their direction of movement, the needles 81, 80 and 79 again knit the yarn 72 in that order. Continued movement of the needles in the clockwise direction causes the needles 82, 81, 80, 79, to approach the yarn 23 to knit the course 71'. In the knitting of this course the needle 82 and the preceding needles knit the yarn 23 and the suture needles 81, 82 likewise knit the said yarn 83 drawing loops of the yarn 23 through loops of the yarn 22 drawn during the knitting of the course 72. The needle 79 does not knit the yarn 23. As the needles again reverse their direction of knitting and move in an anti-clockwise direction to knit the course 72' the needle 80 is held in an elevated position to permit the yarn 23 to be wrapped around its shank and below the latch. During the knitting of this course the needle 81 does not engage the yarn 23 but the needle 82 and following needles 70, 71, 70', 71'.

In the form of the fabric illustrated in Fig. 8, 75

the yarns 22 and 23 are shown as knitted into courses 83, 84, 83', 84' respectively, the arrows 85, 86, 87, 88 indicating the directions of knitting of the said respective courses. The suture shown 5 in Fig. 8 is a two-needle suture, four needles 89, 90, 91 and 92 are indicated. Assuming the cycle to begin with the knitting of the course 83 when the needles are moving in an anti-clockwise direction, the needle 89 and preceding needles knit 10 the yarn 22 in the usual manner while the following needle 90 draws a bight of the yarn 22 through loops previously formed of the yarn 23. The needle 91 does not engage the yarn 22 while the needles are moving in the direction mentioned 15 and the needle 92 does not knit the yarn 22 at any time. Upon the needles reversing their direction of movement and moving in a clockwise direction, the needle 91 engages the yarn 22 and draws a bight of the said yarn through a loop previously 20 drawn of the yarn 23 and the following needles 90, 89, etc. knit the yarn 22 in the usual manner. As the needles continue their movement in the direction last mentioned, the needles 92, 91, 90, 89 approach the yarn 23 during the knitting of 25 the course 83'. During the knitting of this course the needle 92 and preceding needles knit the yarn 23 in the usual manner. The needle 91 draws a bight of the yarn 23 through the loop or bight of the yarn 22 drawn by the said needle 91 during 30 the knitting of the course 84. The following needle 90 also draws a loop or bight of yarn through the loop drawn during the knitting of the course 84. The needle 89 does not knit the yarn 23. Upon the needles reversing their direction 35 of movement and again moving in an anti-clockwise direction, the leading needle 90 is maintained in such a position as to permit the wrapping of the yarn 23 around the shank of the needle 90 and below its latch. The following needles 91, 92, etc. knit the yarn 23 in the usual manner. The following courses are knitting in 40 the same manner as just described in connection with the knitting of the courses 83, 84, 83', 84'.

It will be understood that while the needles 18, 45 19, 20, 21, etc., are knitting their respective wales other needles at the other side of the machine are being similarly actuated to knit a suture for the other side of the stocking or fabric.

In the foregoing description reference has been 50 made to the raising of a leading suture needle to permit the yarn to be wrapped around the shank thereof and below the needle latch; it is not essential that the suture be formed in that way, there being other ways of accomplishing the 55 same purpose as by feeding the yarns to the hook of the said leading needle and thereafter causing the loop to drop below the needle latch.

In the foregoing description reference has been 60 made to needle latches, and to directions of movement of the needles, etc. Specific terms have

been used for descriptive purposes only and not for the purpose of limiting the invention to the precise details of construction recited or to limit the invention to use on any particular type or construction of knitting machine.

From the foregoing, it will be understood that in the various forms of the invention hereinbefore described, the suture is composed of one or two wales in at least one of which two yarns are alternately knitted, that is, one or two loops of one yarn alternate with one or two loops of the other yarn, the knitting of the suture being, preferably, effected with independently movable needles such as are used in Banner and similar types of knitting machines.

Wherever in the claims reference is made to "alternate" and "intermediate" or "intervening," it will be understood that by such limitations there is no intention of limiting "alternate" to the first, third, or fifth course or stitch or in 20 limiting "intermediate" or "intervening" to the second, fourth, or sixth courses or stitches, it being the intention to cover as well the alternating arrangement shown, by way of example, in Figs. 4, 6, 7 and 8.

I claim:

1. A split-work fabric, a suture whereof is composed throughout of two wales only in at least one of which two yarns are alternately knitted and in the other of which both yarns are incorporated, one said yarn being knitted in two consecutive courses at a suture wale.

2. A split-work fabric, a suture whereof is composed of at least two wales in at least one of which two yarns are alternately knitted and in the second mentioned wale of which at least one 35 yarn is knitted in every course.

3. A split-work fabric, the suture whereof is composed of at least two wales and two yarns, one of the yarns floating across at least one of 40 the wales, one only of the said wales consisting of loops alternately knitted of the two yarns.

4. A split-work fabric, a suture whereof is knitted of two yarns and is composed of at least two wales, one of the suture wales comprising 45 alternating knitted loops of the two yarns some of the stitches throughout one of the said two wales including loops of both yarns.

5. A split-work fabric, a suture whereof is composed of two wales only and being alternately 50 knitted with two threads, one of the said threads being knitted in two consecutive courses at a suture wale.

6. A split-work fabric, a suture whereof is composed of two wales only and being alternately 55 knitted with two threads, one of the said threads being knitted in two consecutive courses at a suture wale, the other of the said threads being knitted in single courses only at a suture wale.

ROBERT H. LAWSON. 60
